UNITED STATES PATENT OFFICE

2,423,550

EQUALIZER

Stella M. McMahon Burke, Los Angeles, Calif.

Application August 19, 1944, Serial No. 550,235

4 Claims. (Cl. 2—42)

1

This invention relates to an equalizer.

An object of the invention is to provide a simple, inexpensive construction for inextensibly connecting two parts but which will enable the parts to work readily relatively to each other and if necessary, to assume disaligned or angular relationship with respect to each other.

The improved equalizer has been primarily designed for connecting ends or items of wearing apparel, such as for example the ends of a brassière but it may be used wherever an analogous situation exists. When employed to connect the ends of a brassière the improved equalizer inextensibly connects the ends of the brassière, but permits the top of one side of the brassière to move outwardly at the expense of inward movement of the bottom of the same end as may be occasioned by movements of the body of the wearer. In this manner, the over-all effective length of the equalizer remains substantially constant so that the brassière will not loosen. At the same time the construction is such that working or flexing of the brassière ends, one relatively to the other is readily permitted as may be required by body movement.

With the foregoing and other objects in view, which will be made manifest in the following detailed description and specifically pointed out in the appended claims, reference is had to the accompanying drawings for an illustrative embodiment of the invention, wherein:

Figure 1 is a view in side elevation of the equalizer embodying the present invention in its simplest form;

Fig. 2 is a partial view in side elevation illustrating use of the equalizer embodying the present invention in a more elaborate construction; and

Fig. 3 is a perspective view illustrating the elaborate construction shown in Fig. 2, as applied to the body of the wearer.

Referring to the accompanying drawings wherein similar reference characters designate similar parts throughout, the invention has been illustrated as having been employed to connect the ends of a brassière B, such ends being indicated at 10 and 11. The equalizer embodying the present invention consists of four rings 12, 13, 14, and 15. These rings may be formed of plastic, metal, glass, or any other smooth material having a relatively low coefficient of friction so that the tape 16 that connects them may readily slide therethrough. The tape 16 is preferably a woven tape but may be any adequately strong flexible material. Its ends are secured together

2

so that in effect the tape is endless. This tape is run through the rings in such a manner that there are upper and lower reaches 17 and 18 connecting rings 12 and 13, and 14 and 15 respectively, and crossed reaches 19 and 20 connecting rings 12 and 15, and 13 and 14, respectively. The rings 12 and 14 may be permanently attached to the end 10, such as by loops or tapes 21 and either or both of the rings 13 and 15 may be detachably connected to the end 11, such as by loops 22 which are receivable over buttons 23. Any other form of separable fastener could be employed for this purpose, such as for example, hooks and eyes; snap buttons, or the equivalent. It is not essential that the rings 13 and 15 be detachably connected to the end 11 nor is it essential that more than one of these rings be detachably connected to the end 11. It is highly desirable, however, that the rings be capable of rotating or sliding and thus turning in their respective loops 21 and 22. With the equalizer thus constructed it is obvious that movements of the wearer's body tending to pull the top edges of the ends 10 and 11 apart are accommodated by the tape 16 merely sliding through the rings at the expense of the distance between the rings 14 and 15. Thus, as indicated in Fig. 1 by dotted lines, the exact distance between rings 12 and 13 may slightly increase while the exact distance between rings 14 and 15 slightly decreases. On the other hand, if movements of the wearer's body are such as to require rings 14 and 15 to separate slightly, this is permitted by the tape sliding through the rings and drawing rings 12 and 13 towards each other. The effective overall length of the equalizer remains substantially constant but the ends of the brassière are permitted to readily work relatively to each other in accordance with the demands of the wearer's body.

40 In removing the brassière the loops 22 may be slipped off the buttons 23 or otherwise detached from the end 11 and where only one loop 22 is detachably connected to end 11, this loop may be detached to permit the tape 16 to slide through the rings and thus, in effect, lengthen the overall length of the equalizer to enable the brassière to be slipped over the wearer's head.

In Fig. 1, the equalizer embodying the present invention is illustrated in its most simplified form. However, if desired, in addition thereto there may be upper and lower equalizers combined therewith. Thus, as illustrated in Fig. 2, there may be an upper endless tape 24 which is run through rings 12 and 13 and upper rings 25 and 26 providing two spaced connecting reaches

27 and 28 and crossed reaches 29 and 30. Rings 25 and 26 may be connected to shoulder straps or the equivalent indicated at 31.

A lower equalizer may also be combined with the equalizer on the brassière consisting of a lower endless tape 32 run through rings 14 and 15 and through lower rings 33 and 34, providing connecting reaches 35 and 36 and crossed reaches 37 and 38. The lower rings 33 and 34 may in turn provide a connection for attachment to a skirt or slacks, or may have hose supporters attached thereto. These upper and lower equalizer function in a similar manner in that one side may be extended at the expense of the other to meet the requirements of movements of the wearer's body. At the same time, the overall or effective length of the equalizer is maintained constant. As the rings present a relatively frictionless surface, the tapes readily slide therethrough to meet the various demands placed upon the equalizer.

In the preferred form of construction the crossed reaches of each equalizer employed are arranged against the wearer's body and the connecting reaches are arranged outwardly therefrom.

From the above-described construction it will be appreciated that an improved equalizer is provided which is of relatively simple, durable, and highly efficient construction.

Various changes may be made in the details of construction without departing from the spirit and scope of the invention as defined by the appended claims.

I claim:

1. An equalizer comprising four spaced rings, 35 an endless flexible member slidably extending through the rings and providing two connecting reaches and two crossed reaches, an additional pair of rings and a second flexible member slidably extending through two of the rings of the 40 mentioned four and said additional pair of rings, providing two connecting reaches and two crossed reaches.

2. An equalizer comprising four spaced rings, 45 an endless flexible member slidably extending

through the rings and providing two connecting reaches and two crossed reaches, an additional pair of rings, and a second flexible member slidably extending through two of the rings of the mentioned four and said additional pair of rings, providing two connecting reaches and two crossed reaches, and a second pair of additional rings on the opposite side of the mentioned four rings from said pair of additional rings, and a third flexible member slidably extending through said second pair of additional rings of the mentioned four, providing two connecting reaches and two crossed reaches.

3. An equalizer comprising four spaced rings arranged in pairs and in approximately the same plane, means running through the rings of each pair for attaching the rings of each pair to parts which are to be held against separation, and an endless flexible member connecting said rings have two connecting reaches each of which is positioned against the obverse sides of the rings and two crossed reaches positioned against the reverse sides of the rings, said flexible member slidably extending through said rings.

4. A device as claimed in claim 3 wherein the means connecting the rings of each pair to its respective part is flexible and permits the rings to slidably turn therein.
